[57] **CLAIM**

The ornamental design for a rounded top header extrusion for boat windshields, as shown and described.

DESCRIPTION

FIG. 1 is an end elevational view of a rounded top header extrusion for boat windshields showing our new design, the opposite end being a mirror image thereof; FIG. 2 is a right side perspective view thereof;

FIG. 3 is a left side perspective view;

FIG. 4 is a top plan view thereof;

FIG. 5 is a left side elevational view thereof; and

FIG. 6 is a right side elevational view thereof.

FIG. 1

FIG. 2

FIG. 3

FIG. 4

FIG. 5

FIG. 6
